CLAIM

The ornamental design for a cable closure canister, as shown and described.

DESCRIPTION

FIG. 1 is a front isometric view of a cable closure canister, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom side view thereof.

The broken lines in the drawings depict portions of the cable closure canister that form no part of the claimed design.
